UNITED STATES PATENT OFFICE

MORTON L. PATERSON, OF BOSTON, MASSACHUSETTS, ASSIGNOR TO CONVERSE RUBBER COMPANY, OF MALDEN, MASSACHUSETTS, A CORPORATION OF MASSACHUSETTS

FOOTWEAR

Application filed July 16, 1929. Serial No. 378,598.

This invention relates to improvements in footwear, and more particularly to an improved shoe sole of the type that is intended for sport wear.

5 In certain athletic sports, such as the game of basket ball, the shoes of the players are subject to unusual stresses and wear due to the necessity for sudden starting, stopping and change in the direction of movement. 10 Furthermore, these same conditions make light weight shoes desirable and impose severe strains upon the feet of the players, which must be kept in first-class condition in order to permit effective playing of games 15 of this character.

In accordance with this invention, the material of the shoe sole is arranged to cooperate with the anatomy of the foot in providing the maximum comfort and protection to the 20 wearer under the conditions faced in active sports, such as basket ball, tennis, or the like. Heretofore shoes for this purpose have commonly been provided with soles manufactured from a rubber composition which, for 25 certain purposes such as basket ball, have been provided with corrugations and/or suction cups to provide additional traction and to prevent slipping. More specifically the 30 present invention affords an improved shoe sole of this character which is light in weight and which ensures unusually effective traction under all conditions, and which is therefore effective in aiding quick changes in the direction of movement and the sudden starting and 35 stopping of a player wearing shoes of this character. Furthermore, the material of the shoe sole is also arranged to reinforce the sole at the regions of greatest wear and strain, thereby permitting the shoe to have a 40 relatively long useful life and permitting the continued maintenance of its excellent tractive abilities for a comparatively long period of time, while effectively protecting the wearer's 45 foot and avoiding excess weight.

In order to permit these desirable results, the shoe sole preferably is provided with a continuous marginal flange which may be suitably corrugated and which cooperates with the ribbing upon the intermediate portion 50 of the sole in providing a plurality of

suction cups to afford proper traction and to receive the wear imposed upon the shoe sole. This reinforcement accordingly strengthens a part of the shoe where the imposed strains are high and where objectionable wear or 55 breakage is often likely to occur. In addition, the shoe sole is provided with a pad to support the ball portion of the foot. Preferably this pad is joined to the marginal flange, thus permitting these parts to be reinforced 60 by each other. A pad of this character is particularly advantageous in a shoe used by basket ball players, or individuals participating in similar active sports, where it is 65 usual for the player to pivot upon the ball of the foot, since frequent movements of this character have ordinarily resulted in the rapid wearing away of the portion of the shoe sole that supports the ball of the foot.

Ordinarily basket ball players are especially likely to have trouble with the arches of their feet, due to the heavy strains imposed upon the same by the sudden stops and rapid movements necessitated in this game. 70 Accordingly it is particularly desirable in the case of the shoe used by basket ball players to provide means to support the arch and automatically to oppose any tendency of the latter to fall or break down. In accordance 75 with this invention an integral extension of the marginal flange of the shoe sole is also preferably arranged to extend under the portion of the same that supports the arch of the foot. Preferably this extension decreases 80 in thickness as it extends away from the margin of the sole upon the inner side of the same, and the insole, which may comprise a suitable layer of cushioning material, may be thickened at this portion of the shoe to co- 85 operate with this extension in providing a 90 pad that is adapted to support the arch of the player's foot.

In the accompanying drawings, which exemplify one concrete embodiment of the invention:

Fig. 1 is a bottom view of a shoe sole formed in accordance with the present invention; and

Figs. 2 and 3 are sections on lines 2-2 and 3-3, respectively, of Fig. 1.

- Referring to the accompanying drawings, the numeral 1 designates the sole of a shoe, which includes the forward portion 2 and the heel portion 3, which are connected by a shank 4. Preferably the forward portion 2 of the sole is provided with suitable intermediate ribbing 5 that may be arranged to provide a plurality of suction cups, thus affording excellent traction for the shoe. A suitably corrugated marginal reinforcement 7 extends about the forward portion 2 of the sole and is continued rearwardly along the inner side of the shank 4 to provide a similar reinforcement for the heel portion thereof which may be provided with any suitable ribbing, or may be of any desired design. As shown, the marginal reinforcement may have a somewhat greater depth than the intermediate ribbing 5.
- Preferably a pivot pad 10, that is integral with the material of the shoe sole, is arranged upon the portion thereof that is to support the ball of the foot, this pad being integral with the adjoining portion of the marginal flange 7. The pad 10 may desirably have a thickness which is somewhat less than that of the marginal flange 7, and the ribbing is continued over the pad to provide comparatively shallow irregularities 5a upon this part of the sole. This pad may also be provided with a plurality of additional ribs or corrugations as shown in Fig. 1.
- Upon the inner side of the shank 4, the marginal flange 7 may have a continuation 11 which forms an arch-supporting pad or thickened portion of the shoe sole. Preferably the surface of this pad 11 inclines toward the surface of the shank and extends somewhat less than one-half way across this part of the sole.
- It is evident that a shoe sole constructed in accordance with the present invention has its constituent material advantageously disposed to receive the strains imposed thereon by active play, such as that involved in the game of basket ball and thus to protect the foot of the wearer as well as to provide effective traction without undue weight, and that the portions of the shoe which are likely to be first worn away are especially reinforced in accordance with the present invention. Thus, the marginal flange 7 is arranged to prevent the rapid wearing away of the edge portion of the shoe which otherwise might occur, while pad 10 supports the ball portion of the shoe sole which is subjected to excessive wear by a player who often pivots upon this part of the sole. Furthermore, the arrangement of the element 11 not only is effective in aiding the proper support of the arch of the foot under all conditions, but this part of the shoe sole, as well as the marginal flange 7, aids in the maintenance of satisfactory tractive conditions. Since the pads 10 and 11 are integral extensions of the marginal flange 7, these parts mutually support and reinforce each other and permit the provision of an unusually durable and satisfactory shoe sole for athletes. The sole 1 is sufficiently flexible to permit the weight of the wearer of the shoe to cause the intermediate ribbing 5 to be pressed into engagement with the floor, although this ribbing has somewhat less depth than the marginal flange. I prefer to make the latter with a greater depth so that its engagement with the floor will be assured even after the sole has been subjected to considerable wear, thus ensuring the continued maintenance of excellent tractive conditions and of proper protection to the foot of the wearer.
- I claim:
1. A shoe sole comprising a forward part having a marginal flange with a thickness at least substantially as great as that of the remainder of the forward part of the sole, ribs upon the intermediate part of the shoe sole, and a reinforcing pad integral with the marginal flange and disposed upon the ball portion of the sole, said pad having a depth less than that of the ribs, said ribs being extended over said pad, but there having a relatively shallow depth.
  2. A shoe sole comprising a forward part having an irregularly surfaced intermediate portion, a marginal reinforcement extending about the forward part and having a greater depth than that of the intermediate portion, a reinforcing pad integral with the marginal reinforcement and disposed upon the ball portion of the shoe, said marginal reinforcement extending backwardly along the inner side of the shank to the heel, and an extension of said reinforcement providing a pad upon the shank to support the arch portion of the foot.
  3. A shoe sole comprising a forward portion with an intermediate anti-slip surface, and a marginal flange having a thickness somewhat greater than that of the intermediate part of the forward portion, said flange extending along the inner side of the shank and there having sufficient thickness to form an arch supporting pad, and a pivot pad upon the ball portion of the sole integral with said marginal flange.
  4. A shoe sole comprising a forward portion having an irregular surface providing a plurality of depressions, and a pivot pad upon the ball-supporting portion of the sole having an irregular surface with depressions of less depth than those in the adjoining part of the sole, whereby a relatively greater amount of material is provided to receive the wear imposed by the ball of the foot.
  5. A shoe sole comprising a corrugated forward portion, a pivot pad formed upon said forward portion to support the ball of the foot, a marginal flange integral with said

- pad and extending along the inner edge of the sole to the shank, said flange being thicker than the adjoining shank portion and thus forming an arch-supporting pad.
6. A shoe sole comprising a fore part, a heel part, and a shank part, a marginal flange projecting from the edge of the body of the sole and extending around the edge of the fore part, along the inner edge of the shank part and around the edge of the heel part, a pivot pad on the bottom of the body of the sole adjacent the marginal flange on the inner side of the fore part, having a depth less than that of the marginal flange and extending part way only across the ball of the sole, non-slip corrugations providing projections on the area of the fore part within the marginal flange, the salient surfaces of said projections lying wholly within the plane of the marginal flange, and the depth of the projections on the pivot pad being less than that of the projections on the body of the sole not occupied by the pivot pad.
7. A shoe sole comprising a fore part, a heel part, and a shank part, a marginal flange projecting from the edge of the body of the sole and extending around the edge of the fore part, along the inner edge of the shank part, a pivot pad on the bottom of the body of the sole adjacent the marginal flange on the inner side of the fore part, having a depth less than that of the marginal flange and extending part way only across the ball of the sole, and an arch supporting pad integrally formed with the marginal flange on the shank part and with the body of the sole, and extending inward toward the middle of the shank part and part way only across the shank part, and being gradually tapered in thickness toward its inner extremity.
8. A shoe sole comprising a fore part, a heel part, and a shank part, a marginal flange projecting from the edge of the body of the sole and extending around the edge of the fore part, along the inner edge of the shank part to the heel part, a pivot pad on the bottom of the body of the sole adjacent the marginal flange on the inner side of the fore part, having a depth less than that of the marginal flange and extending part way only across the ball of the sole, non-slip corrugations providing projections on the area of the fore part within the marginal flange, the salient surfaces of said projections lying wholly within the plane of the marginal flange, and the depth of the projections on the pivot pad being less than that of the projections on the body of the sole not occupied by the pivot pad, and an arch supporting pad integrally formed with the marginal flange on the shank part and with the body of the sole, and extending inward toward the middle of the shank part and part way only across the shank part, and being gradually tapered in thickness toward its inner extremity.
9. A shoe sole comprising a corrugated forward portion, a shank, and a heel portion, a marginal rib having a substantially uniform width disposed about the forward portion of the sole, said rib extending along the inner margin of the shank to the heel portion, the inner edge of the rib diverging from its outer edge at the shank to provide a pad shaped to conform to the longitudinal arch, said pad having a surface with a general inclination toward the adjoining surface of the intermediate portion of the shank, whereby the pad conforms to the shape of the arch.
10. A shoe sole comprising a forward portion, a shank and a heel portion, said forward portion being generally characterized by deep corrugations, but having a pivot pad free from deep corrugations adjoining its inner margin to support the ball of the foot, whereby the pad provides a relatively greater amount of material to receive the wear due to pivoting upon the ball of the foot.
11. A shoe sole comprising a corrugated forward portion, a shank, and a heel portion, a marginal flange extending about the edge of said forward portion and having a greater thickness than the remainder of said forward portion, and a pivot pad to support the ball of the foot, said pad being integral with the flange and having a greater average thickness than the adjoining portion of the sole about which the flange extends.
12. A shoe sole comprising a forward portion, a shank, and a heel portion, said forward portion being generally characterized by deep anti-slip depressions, a marginal flange extending about the edge of said forward portion, said flange being extended to the heel portion of the shoe, the flange having two lateral extensions providing pads adjoining the inner margin of the sole, one of said pads being located on the forward portion of the sole to underlie the ball portion of the foot and being free from the deep depressions in the adjoining part of the sole, the other extension being located upon the shank to support the arch, and providing a pad shaped to conform to the contour of the arch of the foot.
13. A shoe sole comprising a forward portion, a shank, and a heel portion, a marginal flange extending about the edge of said forward portion and having a greater thickness than the remainder of said forward portion, said flange being extended to the heel portion of the sole, and a lateral extension of said flange upon the shank of the shoe shaped to conform with the contour of the arch of the foot and to support the latter.
